GEOMETRICAL DEVICE HAVING ARTICULATED
RELATIVELY MOVABLE SECTIONS
Ronald D. Resch, 1009 E. 24 Highway,
Independence, Mo.
Filed June 14, 1963, Ser. No. 287,967
8 Claims. (Cl. 46—1)

This invention relates to geometrical devices, and more particularly, to a device having a plurality of relatively movable, articulated sections.

It has been found that an extremely versatile geometric device can be constructed from a plurality of polygons interconnected at the corners of the polygons into modular arrangement. The sections are pivotally interconnected in a novel pattern so that the module, in an initial closed position with each section abutting an adjacent section, may be moved to an expanded position with spacing between the respective sections by rotating one section in a first direction. Such rotation of the one section moves every other section of the module in a different direction. Reversing the direction of rotation of the section causes the module to return to its closed position.

One feature of the novel arrangement of sections and connectors of the device of this invention is that the size of the device may be increased by merely adding additional sections to the module. A device may be comprised of as many sections as desired so long as the pattern of interconnecting the sections is continued with the added sections.

The novel pattern of interconnection of the sections which results in relative movement of each section of a single module in different directions when one section is rotated to thereby cause expansion or contraction of the module contributes appreciably to the wide variety of uses which may be made of the device. Accordingly, it is the most important object of this invention to provide a device comprising a plurality of geometric sections interconnected in a novel manner into modular arrangement whereby rotary movement of one of the sections of a module results in individual movement of each of the other sections of the module in different directions.

Another important object of the invention is to provide a device wherein all of the sections may be initially arranged in a compact grouping but which may be shifted as a result of the novel arrangement of the sections by movement of one of the sections to an expanded arrangement providing spacing between the respective sections.

Still a further object of the invention is to provide a device which may be moved to the open arrangement of its sections and back to the closed arrangement thereof by the simple expedient of rotation of one of the sections first in one direction and then in the other direction.

A yet further object of the invention is to provide a device which is capable of a wide variety of uses by virtue of its capability of being shifted readily in a predetermined geometric pattern from its closed arrangement covering a relatively small area to its open arrangement covering a relatively large area.

Still other important objects of this invention will be pointed out or will become more apparent as the specification progresses.

In the drawing:

FIGURE 1 is a plan view of one form of the device embodying the principles of this invention showing the device in its closed arrangement;

FIG. 2 is a plan view of the device of FIG. 1 showing the arrangement of the sections in an intermediate position between the closed and open arrangement of the device;

FIG. 3 is a plan view of the device of FIG. 1 showing

2

the arrangement of the sections with the device in its fully open position;

FIG. 4 is a plan view of another form of the device embodying the principles of the invention showing the arrangement of the sections thereof in the fully closed position of the device:

FIG. 5 is a plan view of the device of FIG. 4 showing the arrangement of the sections in a partially open position of the device;

FIG. 6 is a plan view of still another device embodying the principles of this invention showing the arrangement of the sections when the device is in its fully closed position;

FIG. 7 is a plan view of the device of FIG. 6 showing the arrangement of the sections when the device is in a partially open position; and

FIG. 8 is a fragmentary, perspective view of another device embodying the principles of this invention wherein the sections are prisms.

Referring initially to FIGURE 1, the device embodying the principles of this invention is broadly denoted by the numeral 10 and comprises a plurality of geometric sections which, in this form of the device 10, are squares. There is a centrally disposed section 12 circumscribed by a plurality of sections having side margins equal to the margins of section 12 and numerated 14, 16, 18, 20, 22, 24, 26 and 28. The sections 12-28 comprise one module of the device 10 and it will be noted that the sections 16, 20, 24 and 28 are positioned with one side margin of each section lying in substantial abutting disposition with respect to a corresponding side margin of the central section 12.

The abutting side margins of sections 16, 20, 24 and 28 are in coextensive alignment with the respective side margins of central section 12. Section 18 is positioned between sections 16 and 20 and has a pair of its adjacent side margins positioned coextensively with and in substantial abutting disposition with respect to the proximal margins of sections 16 and 20. Similarly, the sections 22, 24 and 14 are positioned between the sections 20 and 24, 24 and 28, and 28 and 16 respectively, as shown in FIG. 1. Thus, it is apparent that each of the outer sections 14-28 are positioned with two side margins of each section in substantial abutting disposition with respect to two imaginary straight lines lying along any two adjacent side margins of the central section 12 when the module is in the closed position illustrated in FIG. 1.

Device 10 is shown in FIGS. 1, 2 and 3 as comprising but a single module which includes a central section 12 and a ring of outer sections 14-28 disposed in continuous circumscribing disposition with respect to central section 12. It will be readily understood, however, that device 10 could include more sections interconnected with the adjacent sections. It is deemed sufficient, however, to explain the principles of this invention to show device 10 comprised of but one module.

The sections of the module of device 10 are interconnected by pivot structures or hinge means 30 which may take any form. It is sufficient that particular corners of the section be pivotally interconnected with proximal corners of adjacent sections so that one section is free to rotate at its corner about the point of connection with the adjacent section. The hinges 30 chosen for illustration comprise elongated strips of flexible material having opposed end margins thereof firmly secured by adhesive or the like to the sections interconnected by the hinges. By referring to FIGS. 1, 2 and 3 of the drawing, it is clearly apparent that there is a hinge 30 pivotally interconnecting each corner of the central section 12 with a corner of the outer sections 28, 16, 20, and 24. There is also provided a hinge 30 connecting a pair of the corners of the sections 14, 18, 22 and 26

with the proximal corners of the adjacent sections 16, 20, 24 and 28. Each corner of the respective sections is interconnected with but a single corner of another section of the module.

By virtue of the arrangement of the sections of the module and the novel pattern of interconnection thereof, it is possible to move each section of the module in a different direction and to expand the module from the closed position thereof by simply rotating a single section of the module. For example, if section 12 is rotated in a clockwise direction as viewed in FIG. 2, the other sections of the module are caused to both rotate and translate to provide spacing between the sections. Such clockwise rotation of section 12 causes section 16 to rotate in a counterclockwise direction and also to translate in a direction indicated by the arrow at the top of FIG. 2. Section 20 also rotates in a counterclockwise direction but translates in a direction at right angles from the direction of translation of section 16 and in the direction indicated by the arrow proximal section 20 at the right of FIG. 2. In a similar manner, section 24 is caused to rotate in a counterclockwise direction but in the direction indicated by the arrow at the bottom of FIG. 2, while section 28, also rotating in a counterclockwise direction, translates in the direction of the arrow beside section 28 at the left of FIG. 2.

Simultaneously, the clockwise rotation of section 12 causes clockwise rotation of sections 18, 22, 26 and 14 and translational movement of the sections on diagonal lines radiating outwardly from the axis of rotation of section 12 and passing through the respective sections 18, 22, 26 and 14.

An inspection of FIG. 2 reveals that this movement of the sections produces spacings 32 between the central section 12 and the outer sections 14-28. There are four spacings 32 for each module. Continued rotation of section 12 through an arc of 45° causes the arrangement of the sections illustrated in FIG. 3 wherein the spacings 32 cover a maximum area and are as large as the individual sections of the device 10. It will be readily understood that rotation of section 12 through an equal arc in a counterclockwise direction will result in the shifting of the individual sections of the module back into the initial position shown in FIG. 1 wherein the side margins of the sections are in close abutting relationship with the side margins of adjacent sections. The area covered by device 10 in the open position thereof illustrated in FIG. 3, is vastly greater than the area of the device 10 shown in its closed position in FIG. 1.

Another form of the invention is illustrated in FIGS. 4 and 5 wherein a device 34 comprises a plurality of triangular sections. There is a central equilateral, regular section 36 surrounded by sections 38, 40 and 42, each having one side margin thereof lying in coextensive, substantial abutting disposition with respect to a side margin of central section 36. Triangular sections 44, 46 and 48 having sides of the same size as sections 36-42 are positioned between the sections 38 and 40 as illustrated in FIG. 4.

Similarly, there are provided sections 50, 52 and 54 between sections 40 and 42 and sections 56, 58 and 60 between sections 42 and 38 as shown in the drawing. It will thus be seen that sections 38-60 are disposed in continuous, circumscribing, proximal relationship to the perimeter of central section 36, with each of the sections 38-60 having side margins thereof positioned in coextensive, substantially abutting relationship with the side margins of an adjacent outer section. The sections of device 34 are pivotally interconnected as shown in FIGS. 4 and 5 by means of pivot structures or hinges 62 which may be identical to hinges 30. There is a hinge 62 pivotally interconnecting each corner of central section 36 with one corner of the adjacent sections 38, 40 and 42 as shown clearly in FIG. 5.

Additionally, a pair of the other corners of each outer

section 38-42 is pivotally interconnected by hinges 62 with the proximal corners of adjacent sections as illustrated. Thus, section 38, in addition to being pivotally interconnected at one corner to section 36, is pivotally interconnected at the other corners to the proximal corners of respective sections 44 and 60 as shown. Likewise, section 40 is pivotally interconnected to section 36 at one corner and at the other corners to the proximal corners of sections 48 and 50 as shown. In the same manner, section 42 is pivotally interconnected at one corner to section 36 and at each of the other corners to the corresponding proximal corners of respective sections 54 and 56 as shown. Additionally, section 58 is pivotally interconnected at a pair of corners thereof to corners of sections 56 and 60, while section 46 is pivotally interconnected to sections 44 and 48, and section 52 is pivotally interconnected to sections 50 and 54, all as shown clearly in FIGS. 4 and 5. It will be noted that in device 34, as hereinabove set forth with respect to device 10, a given corner of each of the sections of the module is connected to but a single corner of an adjacent section.

The sections of the module can each be caused to move in a different direction by simply rotating a single section of the module. Thus, if central section 36 is caused to rotate in a clockwise direction, the other interconnected sections of the module are each caused to rotate toward positions shown in FIG. 5. In addition to rotation, each section is caused to translate generally along lines passing through the axis of rotation of the rotating central member 36 and extending through the corresponding sections. Such movement of the sections causes spacings 64 between the central section 36 and the outer sections 38-60 as shown in FIG. 5. Continued rotation of central section 36 causes enlargement of the spacings 64 as will be readily understood. Likewise, rotation of section 36 in the opposite direction from that illustrated by the arrow in FIG. 5 causes the return of the sections of the module to the closed position thereof as shown in FIG. 5. It can be appreciated that device 34 occupies considerably larger area in its open position than in the closed position shown in FIG. 4.

Referring now to FIGS. 6 and 7, the form of the invention comprises a device 66 similar to device 10 wherein the sections are rhomboidal. The arrangement of the sections is identical to that set forth in detail with respect to device 10 and will be omitted for the sake of brevity. It should be pointed out, however, that the corners of the sections are interconnected in a manner corresponding with device 10 and by pivot structures or hinges 68 which may be identical to pivot structures or hinges 30. The module of device 66 includes a central section 70 and a plurality of circumscribing sections 72, 74, 76, 78, 80, 82, 84 and 86. Viewing FIG. 7, it will be seen that rotation of one of the sections of device 66, for example section 70, imparts both rotational and translational movement to the other sections of the module as set forth with respect to device 10. Such movement is in a different direction for each section of the module and results in spacings 88 between the sections. Rotation of central section 70 in the opposite direction causes the module to return to its closed position as shown in FIG. 6. Obviously, device 66 occupies a relatively larger area in its open position than in the closed position thereof.

The particular construction of the hinges 30, 62 and 68 form no part of the invention per se, it being sufficient that they are flexible to permit pivotal interconnecting of the sections at their corners in a manner to permit ready movement of the sections into the fully closed position thereof with the side margins of the sections lying in substantial abutting disposition with respect to the proximal side margins of adjacent sections. The hinges 30, 62 and 68 must likewise be flexible to permit shifting of

the sections to the closed positions of the respective devices 10, 34 and 66 as herein previously explained.

The devices chosen for illustration have included squares and rhomboidal sections, as well as triangular sections. However, sections which are parallelograms of any specific shape are suitable for constructing devices according to the principles of this invention.

It is contemplated by this invention that the sections of the devices 10, 34 and 66 could be constructed from relatively flat sheet material. Thus, the description to this point has been directed toward sections comprised of squares, triangles, and rhombuses. However, the invention could be equally advantageously carried out if the sections were constructed from blocks of material having a substantial third dimension. Thus, device 10 could be constructed from prisms, it being sufficient that one side thereof is square. Likewise devices 34 and 66 could also be constructed from prisms having one side thereof triangular and rhomboidal respectively.

The device 90, fragmentarily illustrated in FIG. 8, includes a plurality of sections 92 which comprise prisms interconnected along their corners by elongated strips 94 of flexible material. The device 90 is shown in its fully open position to present spacings 96 between the respective sections 92.

The devices constructed according to the principles of this invention are quite versatile. For example, it has been found that devices constructed with one or more modules of articulated sections is particularly well adapted as a toy wherein a single section may be grasped to permit expansion or contraction of the device by simply manually rotating one of the sections. The sections may be colored in a variety of ways to impart attractiveness to the object. It is contemplated that the individual sections of the devices could be molded from plastic material or the like and that they could take the form of open-top vessels into which might be placed objects such as children's blocks or the like. The blocks could be readily removed and replaced with other blocks which might be of different colors so that the child could change the geometric pattern formed by the sections of the devices.

Further, it has been found that the novel construction of devices in the manner contemplated by this invention results in a device which is particularly well adapted for use as a mat to be placed in protective disposition over a planar surface. For example, devices constructed in this manner are well suited for use by housewives or the like in placing under hot dishes, kettles or the like for protecting tables and other surfaces. When it is desired to use the device with a relatively small vessel, the device may be employed in its closed position. If, however, it is necessary to protect the surface from a much larger vessel, the device may be readily moved to the expanded position thereof wherein an appreciably greater surface is thereby protected.

Still other very important uses which have been found for devices of this construction include the presentation of animated signs. One such use contemplates the presentation of certain information on an exposed face of the sections when the device is in its closed position. Movement of the device to its open position may result in obliteration of the information first displayed and the exposure of other information which was not observable when the device was in its closed position. This may be achieved by virtue of having information appearing at the spacings 32, 64, 88 or 96 which could not be seen until the device reached its open position. The result could also be achieved by the use of special light-reflective surfaces whereby the shifting of the sections from one position to the other disposes the surfaces with respect to the observer in such a manner that information on the sections observable at one position thereof could not be discerned at another position, whereas different information would thereupon be displayed. A variety of

means could be utilized for motivating the shifting of the device from the closed to the open position and the return to the closed position. Such motivation is enhanced and appreciably simplified by virtue of the fact that it is merely necessary to motivate but one of the sections to achieve resultant motivation of all of the rest of the sections in the manner hereinabove set forth.

It should be stressed that although a single module has been shown for each device for illustrative purposes, the devices may comprise many modules interconnected in the pattern hereinabove set forth. Additionally, each module might have a single row of sections therearound or even a few sections attached to the outer sections of the module. If the pattern of interconnection which has heretofore been set forth and is clearly illustrated in the drawing is followed, the other additional sections of the device will operate in a similar manner to those described.

Having thus described the invention, what is claimed as new and desired to be secured by Letters Patent is:

1. A geometric device comprising:
a plurality of relatively shiftable, polygonal sections in modular arrangement to define a module and including a central section and a plurality of outer sections, said outer sections being disposed in continuous circumscribing, proximal relationship to the perimeter of said central section, each of said outer sections having side margins thereof positioned in coextensive, substantially abutting relationship with the side margin of an adjacent outer section, a side edge of an outer section adjacent to said central section being disposed in proximal coextensive, substantially abutting disposition with respect to an adjacent side of said central section when the module is in a closed condition;
means pivotally interconnecting each corner of the central section with the proximal corner of the outer section adjacent thereto; and
means pivotally connecting a pair of the other corners of each outer section with the proximal corners of the outer sections adjacent thereto to permit movement of all of the sections when said central section is rotated, a corner of each section being interconnected with but a single corner of another section of the module.
2. A device as set forth in claim 1 wherein said sections are parallelograms.
3. A device as set forth in claim 1, wherein said sections are square.
4. A device as set forth in claim 1, wherein said sections are triangular.
5. A device as set forth in claim 1, wherein said sections are rhomboidal.
6. A geometric device comprising:
a plurality of relatively shiftable square sections in modular arrangement to define a module and including a central section and a plurality of outer sections, said outer sections being disposed in continuous, circumscribing, proximal relationship to the perimeter of said central section, said outer sections being positioned with two side margins of each outer section in substantial abutting disposition with respect to two imaginary straight lines lying along two adjacent side margins of the central section when the module is in a closed position; and
means pivotally interconnecting the sections of the module, said means including first structure interconnecting the corners of said central section to the proximal corners of respective, adjacent outer sections and second structure interconnecting a corner of each of said respective, adjacent outer sections adjacent to its said proximal corner to the proximal corner of the outer section adjacent thereto, a corner of each section being interconnected with but a single corner of another section, whereby the sections may

be shifted to an expanded position of the module by rotation of one of said sections.

7. A geometric device comprising:
 a plurality of shiftable, rhomboidal sections in modular arrangement to define a module and including a central section and a plurality of outer sections, said outer sections being disposed in continuous circumscribing, proximal relationship to the perimeter of said central section, said outer sections being positioned with two side margins of each outer section in substantial abutting disposition with respect to two imaginary straight lines lying along two adjacent side margins of the central section when the module is in a closed position; and
 means pivotally interconnecting the sections of the module, said means including first structure interconnecting the corners of said central section to the proximal corners of respective, adjacent outer sections and second structure interconnecting a corner of each of said respective, adjacent outer sections adjacent to its said proximal corner to the proximal corner of the outer section adjacent thereto, a corner of each section being interconnected with but a single corner of another section, whereby the sections may be shifted to an expanded position of the module by rotation of one of said sections.

8. A geometric device comprising:
 a plurality of relatively shiftable, triangular sections in modular arrangement to define a module and including a central section and a plurality of outer sections, said outer sections being disposed in continuous circumscribing, proximal relationship to the perimeter of said central section, each of said outer sections having side margins thereof positioned in coexten-
